UNITED STATES PATENT OFFICE.

JAMES H. CANNON, OF LOS ANGELES, CALIFORNIA.

ELECTRIC HAIR CURLER.

Application filed July 7, 1924. Serial No. 724,557.

My present invention is an electric hair curler especially designed for the waving of hair and suitable for the production of the so-called "marcel", or other waves; and it is an especially object of this invention to provide an electrically heated hair curler of advantageous form with effective and durable heating means. All parts of my hair curler are capable of being manufactured and assembled at moderate cost, although not easily liable to accidental breakage or derangement.

My invention comprises an electrical heating element of novel design adapted to be incorporated in what may be termed a "hammer" or T type of hair curler; and it comprises also an advantageous exterior or enclosing shell construction comprising a split or two-part casing held together at two or more points by clips or ferrules, some of which may be in the form of caps, although one of said clips or ferrules may be the upper end of an insulating hollow handle through which the lead wires to said heating element may extend.

Other objects of my invention will appear from the following description of alternative embodiments thereof, taken in connection with the appended claims and the accompanying drawings, in which—

Fig. 1 is an elevational view of the head or curler end of a heater of my improved design, with a strand of hair wound thereon.

Fig. 2 is a longitudinal section through a heater of the same type.

Fig. 3 is an additional longitudinal section, which may be regarded as taken in the plane indicated by the line 3—3 of Fig. 2.

Fig. 4 is a top plan view taken in the direction indicated by the arrow 4 of Fig. 3, the parts being broken away.

Fig. 5 is a transverse sectional view taken as indicated by the line 5—5 of Fig. 3.

Fig. 6 is a separate illustration of an alternative type of heating element herein-after referred to.

Referring to the details of that specific embodiment of my invention illustrated in Figs. 1 to 5 inclusive, the heating element 11 of my hair curler may be housed within a substantially T-shaped casing or shell, preferably formed in two sections 13 and 14, these sections being shown as held together by clips or ferrules comprising caps 15, 15', and optionally comprising also the

upper end 16 of a handle 17, through which extend conductive wires 18, 18', by which electricity may be supplied to the heating element 11.

The heating element 11 may be of any usual or preferred design, but I consider it especially advantageous to form the same by winding a comparatively fine resistance wire, such as a nickel chromium wire 19, in suitable spaced grooves 20, such as spiral grooves, formed in the exterior surface of an insulating body, the said insulating body being shown as provided with shell-spacing projections in the form of terminal flanges 21, 21', shown as provided with notches 22, 22' through which an end of the resistance wire may be returned by way of a substantially central longitudinal channel 23—to which extends a lateral opening 24 to permit the connecting of the free ends of the wire 19 with the main conductors 18, 18'.

Any usual or preferred connecting means may be employed in securing the ends of the resistance wire 19 to the main conductors 18, 18'; and my preferred means for this purpose may comprise conductive leads 25, 25', having flat ends deformed to provide channels 26, 26' adapted to be crimped about both the ends of the main conductors 18, 18' and the extreme ends of the resistance wire 19 wound loosely on the leads 25, 25'.

Although air-insulation, as provided by the mentioned spacing of the heating element 11 from the surrounding shell by means of the flanges 21, 21', may be relied upon effectively to insulate the wire 19 from the surrounding casing, I may optionally employ in the head of my electrical heater additional insulating or spacing means such as mica plates 27, 28; and the insertion of these may be especially desirable when the insulating body of my heating element is substantially semi-circular in cross sectional outline, as best shown in Figs. 3 and 4. The insertion of insulating materials in the transverse bar of the T-shaped head member may, however, be entirely dispensed with, by, for example, the employment of an insulating spool of the character best shown in Fig. 6, this spool being substantially circular in cross sectional outline, although provided with a longitudinal channel 27^a extending to the slots 22^a, 22'^a in the flanges 21^a, 21'^a by which air-spacing is effected, the ends of the insulating wire 19^a being 110

carried out through a lateral opening 24^a and optionally connected substantially in the manner already described.

Insulating cores 29 or 29^a of the characters disclosed in Figs. 2, 3, 4 and 6 may advantageously be cut from a material such as lava; and this same material may advantageously be employed in the stem 30 of a T-shaped head of the character described, 5 separate longitudinal channels 31, 31' being shown as provided for the respective conductive leads 25, 25', and any desired means such as a screw or screws 32, 32', being employed to connect said stem with the upper end 16 of the handle 17, or its equivalent. The main conductive wires 18, 18' may advantageously be carried through the handle 17 in separate insulating tubes 33, 33'; and a connecting plug 34, provided with conductive pins 35, 35' connected with the main conductors 18, 18', may be spaced from and secured to the stem 30, or its equivalent, by means such as an assembly plate 36, shown as secured to the insulating plug 34 by 20 means of a band 37, the mentioned screws 32, 32' being preferably carried not only through the respective sections 13, 14 of the shell comprising the stem 30, but also through the upper end of said assembly 25 plate.

Although, I have herein described all structural details of a complete hair curler device, it should be understood that I attach especial importance to the described construction of the heating element 11, including the alternative form 11^a thereof shown in Fig. 6, and to the three-point clip construction by which I may hold an outer casing in insulated relationship thereon. To 30 prevent accidental or unauthorized removal of the caps 15, 15', or their equivalent, they may advantageously be crimped or otherwise deformed in place, substantially as indicated at 38, 38' in Fig. 1.

Although I have herein described one complete embodiment of my invention and an advantageous alternative construction of a heating element suitable for use therein, it should be understood that various features described might be independently employed, and also that various modifications might be made, by those skilled in the art, without the slightest departure from the spirit and scope of my invention, as the same is indicated above and in the following 50 claims.

I claim as my invention:

1. An electric hair curler comprising: a T-shaped head consisting of a closed hollow shell having a stem; an insulator entirely enclosed within said shell; an electric heating element wound on said insulator; a hollow handle associated with said stem of the head and communicating therewith; and connecting means for said heating element comprising circuit conductors connected to said element and extending from said shell directly into the hollow stem and handle. 60

2. A heater as described in claim 1 in which said shell is split in a plane extending 70 through the bar of said head.

3. A heater as described in claim 1 in which said shell is split in a plane extending through the bar of said head and in which the sections of said shell are held together by means engaging the ends of the 75 respective sections.

4. A heater as described in claim 1 in which said T-shaped head is held together by means comprising caps at the ends of the 80 bar thereof.

5. A heater as described in claim 1 in which said T-shaped head is held together by means comprising caps at the ends of the bar thereof and comprising also an end of the 85 insulating handle through which conductive leads extend.

6. In a hair curler: a casing; an insulator within said casing; an electrical heating element wound on said insulator; connecting 90 means for said heating element comprising leads of conductive material channeled at one end for crimping, the ends of said heating element being wound about said leads and held in conductive contact with said leads by the crimping of said channeled ends; a longitudinally grooved insulating element within which said leads are spaced apart; a handle through which said lead conductors extend; a connecting plug near 100 one end of said handle; and an assembly plate provided with means for securing the same within said handle.

7. In an organization as described in claim 6, a two-part T-shaped shell surrounding 105 said heating element and held in assembled relationship partly by insertion in said handle.

In testimony whereof, I have hereunto set my hand at Los Angeles, California, this 28 110 day of June, 1924.

JAMES H. CANNON.
